Alfred E. Linneros ^{Inventor}

By Milton Thomas, Jr.

Attorney

UNITED STATES PATENT OFFICE.

ALFRED E. LINNEROS, OF CHICAGO, ILLINOIS.

UNDERGARMENT.

1,263,576.

Specification of Letters Patent. Patented Apr. 23, 1918.

Application filed June 29, 1917. Serial No. 177,708.

To all whom it may concern:

Be it known that I, ALFRED E. LINNEROS, a subject of the King of Sweden, residing at Chicago, in the county of Cook and State 5 of Illinois, have invented new and useful Improvements in Undergarments, of which the following is a specification.

This invention relates to men's undergarments, and its object is to provide a novel 10 and improved connection between the shirt and drawers portions of the garment, whereby the latter is given a shoulder suspension.

Another object of the invention is to provide the garment with a scrotal suspensory bag which is a part of the drawers, and also 15 to provide the latter with an apron or shield.

The objects stated are attained by means 20 of a novel combination and arrangement of parts to be hereinafter described and claimed, and in order that the same may be better understood, reference is had to the accompanying drawing forming a part of 25 this specification.

In the drawing,

Figure 1 is a front elevation of the garment, with parts broken away, and Fig. 2 30 is a sectional detail of the suspensory bag.

Referring specifically to the drawing the garment is composed of a shirt 5 and drawers 6, the former buttoning up in front similar to an ordinary undershirt. The drawers also button up in front and they are detachably connected to the shirt, the latter carrying shoulder straps 7 in front and at the rear, which extend down to the waist line and have button holes 8 for connection with buttons 9 on the waist portion of the drawers. Any other detachable fastening devices 35 may be provided for attaching the drawers to the shirt. The straps 7 extend across the shoulders of the shirt and a shoulder suspension for the drawers is therefore produced. The strap ends are provided with a plurality of button holes 8 so that the necessary adjustment may be made. By providing the hereinbefore described con-

nection between the shirt and the drawers, the latter are effectually prevented from 50 dropping down or sagging, and the garment becomes practically a one-piece garment or union suit.

At the crotch of the drawers 6 is a padded opening 10, and beneath the latter is a 55 scrotal suspensory bag 11. These parts are produced by making an opening in the crotch and sewing or otherwise mounting over the opening a piece 12 of flannel or other soft material in which the opening 10 60 is made, and also an opening beneath which the bag 11 is secured. As the drawers are shoulder-suspended, no straps or other attaching or retaining devices are necessary 65 for the suspensory bag.

In order to shield the parts for which the opening 10 and the bag 11 are designed, the front of the drawers 6 is provided with an apron 13 shown partly broken away in Fig. 1. This apron is attached to the waist 70 portion of the drawers, and it depends therefrom to come between the parts 10 and 11 and the outer shirt and trousers of the wearer. As the apron is secured to the drawers it is not subject to upward displacement or wrinkling. 75

I claim:—

1. An undergarment having a crotch opening, a suspensory bag attached to the garment adjacent to said opening, and an 80 apron attached to the front portion of the garment and extending down over the crotch opening and the suspensory bag.

2. An undergarment comprising separate 85 shirt and drawers sections, shoulder straps carried by the shirt section, a detachable connection between said straps and the drawers section, the drawers section having a crotch opening, a suspensory bag attached to the drawers adjacent to said opening, and an 90 apron attached to the front portion of the drawers section and extending down over the crotch opening and the suspensory bag.

In testimony whereof I affix my signature.

ALFRED E. LINNEROS.
